UNITED STATES PATENT OFFICE.

ARTHUR J. SCAIFE, OF CLEVELAND, OHIO, ASSIGNOR TO THE WHITE COMPANY, OF CLEVELAND, OHIO, A CORPORATION OF OHIO.

CARBURETER.

1,136,276.

Specification of Letters Patent.

Patented Apr. 20, 1915.

Application filed July 6, 1914. Serial No. 849,126.

To all whom it may concern:

Be it known that I, ARTHUR J. SCAIFE, a citizen of the United States, residing at Cleveland in the county of Cuyahoga and State of Ohio, have invented a certain new and useful Improvement in Carbureters, of which the following is a full, clear, and exact description.

This invention is a carbureter designed especially for supplying to an internal combustion engine, uniform mixtures of air and gas, especially natural gas, in contradistinction to such carbureters as additionally vaporize gasoline for mixture with the air.

15 The construction is such that the mixture produced thereby is substantially uniform, irrespective of the speed of the engine.

The invention consists in the construction and combination of parts shown in the drawing and hereinafter described and definitely pointed out in the appended claims.

In the drawing Figure 1 is a central vertical section of a carbureter embodying the said invention. Fig. 2 is a sectional view in the plane of line 2—2 on Fig. 1. Fig. 3 is an elevation from the left side of Fig. 1. Fig. 4 is a bottom plan view; and Fig. 5 is a top plan view of the valve.

Referring to the parts by reference characters, 10 represents a valve casing having a horizontal cylindrical recess in which the cylindrical throttle valve 12 is rotatably mounted. A hole 10^a is cut through the lower wall of this valve casing for the admission of air, and another hole 10^b is cut through the upper wall of said valve casing and connects the same with the tubular mixing chamber 13 whose walls are formed integrally with the valve casing, and which is adapted for connection at its upper end with the inlet manifold of the engine. These two holes are preferably, but not necessarily, circular. This tubular mixing chamber is shown surrounded by a water jacket of familiar construction, but this is not at all essential to the invention.

This valve 12 contains at one end thereof a gas chamber 15, to which gas is admitted through the axially placed tubular stem 16. 50 Gas is discharged from this chamber into the mixing chamber 13 through one or more or all of the jet holes 17 formed through the cylindrical wall of this chamber in such positions that they will be progressively uncovered by the turning of the valve in one

direction; that is to say, will be progressively brought into communication with the holes 10^a in the upper wall of the valve casing. By so turning the valve, therefore, the effective area of the holes through which gas is delivered into the mixing chamber will be increased.

An air hole 18 is formed through valve 12, in such position that it will be progressively uncovered at both ends by the turning of the valve in the same direction which progressively uncovers hole 17. That is to say, the ends of this hole 18 will be brought progressively into communication with the lower hole 10^a and the upper hole 10^b in the walls 70 of the valve casing. The hole 18 is of such shape that as its ends are uncovered, its effective area for the passage of air will increase in proportion to the increased effective area of the holes 17 through which the 75 gas escapes from said chamber. Therefore, to whatever extent the valve may be opened, the relative volume of air and gas admitted to the mixing chamber will remain unchanged.

At that end of the valve, preferably, which is adjacent to the air hole 18, there is an axially disposed stem 19 which projects out of the valve casing; and the valve operating lever 20 is secured to the outer end 85 of this stem. This lever may lie between one fixed stop 22 and one adjustable stop 23 so as to limit its movement between a wholly closed and wholly open position.

In addition to the hole 18, there is, 90 through the valve adjacent thereto, a second small hole 25 which is so placed that when the valve is closed in the sense that the air hole 18 is fully covered, and all of the jet holes 17 are covered, this hole remains uncovered at both ends, and in open communication with the holes 10^a, 10^b in the valve casing. This hole is put in so as to make it easier to turn over the engine by hand, when the throttle valve is closed, because through 95 this hole 25 some air may flow when the engine is being turned over, thereby preventing the formation of any considerable degree of vacuum in the engine cylinders.

The specific shape and arrangement of the 105 air holes, and the gas outlet holes, as shown in the drawing, are not essential; and may be varied as desired, so long as they are such that as the valve is turned, the relation between the uncovered parts of the air hole 110

and gas discharge holes is substantially preserved.

It will be noted also that the valve, intermediate of the two ends of the air holes 18 and 25 is hollowed out or shell like. That, however, is not an essential to the invention, but is merely an incident of the manner in which the valve shown was made. The size and location of the ends of the holes 18 and 25 are the things which determine the action thereof.

The invention is shown in the drawing in the precise form in which it has been practically successful in using natural gas delivered into the gas chamber through the hollow stem at a pressure of three ounces.

Having described my invention, I claim:

1. In a carbureter, the combination of a cylindrical valve casing through the walls 20 of which are two holes, one open to the atmosphere, a mixing chamber with which the other hole communicates, and a cylindrical valve rotatably mounted in said casing, said valve having in one end a gas chamber, 25 through the cylindrical wall of which are discharge orifices which will be progressively uncovered and placed in communication with the mixing chamber as the valve is turned, and said valve having also through 30 it an air hole which will be progressively uncovered and placed in communication with both holes in the valve casing by the said turning of the valve, and means for delivering gas into said gas chamber.
- 35 2. In a carbureter, the combination of a cylindrical valve casing through the walls of which are two holes, one open to the atmosphere, a mixing chamber with which the other hole communicates, and a cylindrical valve rotatably mounted in said casing, said valve has in one end a gas chamber provided

with a tubular axially disposed gas inlet stem, there being through the cylindrical wall of said gas chamber discharge orifices which will be progressively uncovered and 45 placed in communication with the mixing chamber as the valve is turned, said valve having also through it an air hole which will be progressively uncovered and placed 50 in communication with both holes in the valve casing by the said turning of the 55 valve.

3. In a carbureter, the combination of a cylindrical valve casing through the wall of which are two holes, one open to the atmosphere, a mixing chamber with which the other hole communicates, and a cylindrical valve rotatably mounted in said casing, said valve has in one end a gas chamber provided with a tubular axially disposed gas inlet 60 stem, there being through the cylindrical wall of said gas chamber discharge orifices which will be progressively uncovered and placed in communication with the mixing chamber as the valve is turned, said valve having also through it an air hole which will be progressively uncovered and placed in communication with both holes in the valve, and there being also through said valve a small 65 air hole which will remain uncovered at both ends and therefore in communication with both holes through the walls of the valve casing when all of the other holes referred to are covered.

In testimony whereof, I hereunto affix my signature in the presence of two witnesses.

ARTHUR J. SCAIFE.
